James Murphy

UNITED STATES PATENT OFFICE.

JAMES MURPHY, OF MIDDLETOWN, CONNECTICUT.

PACKAGE-TIE.

1,369,348.

Specification of Letters Patent. Patented Feb. 22, 1921.

Application filed September 15, 1919. Serial No. 323,944.

To all whom it may concern:

Be it known that I, JAMES MURPHY, a citizen of the United States, residing at Middletown, in the county of Middlesex and State 5 of Connecticut, have invented a new and useful Improvement in Package-Ties, of which the following is a specification.

This invention relates to a bundle or package tie of that type, consisting of a metal 10 fastener to which one end of a cord or other flexible material is attached and so arranged that the other or free end of the cord can be securely fastened, and doing away with the necessity of severing the cord when the 15 bundle or package is to be opened. The chief object of this invention is to provide an improved, simple and inexpensive device of this character that may be readily manipulated and used repeatedly on all packages 20 of letters or other mail matter, thus saving a large expense for cord as now used in the mail service. The above and other objects are attained in the preferred form of this invention illustrated in the accompanying 25 drawings in which—

Figure 1 is a plan view, Fig. 2 is a lateral view, Fig. 3 is an edge view from a point located at right angles to the point of view of Fig. 1. Figs. 4 and 5 are views illustrating the manner of using the device.

My improved device for fastening bundles or packages comprises a flexible binding material such as cord, twine, tape or other similar material and a fastening part in the 35 form of a plate made of metal or some other inflexible material.

The size and shape of the plate are shown in the illustration.

The plate consists of a projection or arm 40 (1) a perforation (2) for the reception of the cord which when knotted at the extremity is prevented from slipping back, a stud (3) punched up from the body of the plate,

and an arrow-head shaped cleat comprising a shank (4) connecting the head 5 of said 45 cleat with the above described parts, said cleat also comprising lateral prongs or arms 8 forming notches 6—7 for the reception of the binding material. The cleat part is somewhat elevated above the general plane 50 of the plate, and its pointed end projecting downwardly at an angle to said plate.

The use of this invention may readily be seen by referring to Figs. 4 and 5. In applying this invention the plate is placed at 55 the center of one surface of the package, the cord is then carried around the package in the direction shown by the arrow. After crossing the surface opposite to that upon which the plate rests the cord is brought 60 back to the plate and under the stud (3). It is now carried around the package in a direction at a right angle to the initial turn until it is brought back to the plate where it is slipped into the notch (6) then over 65 the shank (4) and into the notch (7) then under the shield-shaped part of cleat and back into notch (6) where it binds or jams under the first turn at this point, thus being 70 securely held and rendering slipping impossible.

To release the package it is merely necessary to reverse the order of the above described turns.

Having thus described my invention what 75 I claim is:

A package tie including a plate having means for attachment of one end of a flexible fastener, means to receive said fastener intermediate its ends, and an arrow-head shaped cleat having its narrow part resting above the plane of the plate and its pointed end projecting downwardly at an angle to said plate.

JAMES MURPHY, M. D.
